TRANSPORTABLE SHELTER

Norman Marx, Hammond, Ind.

Application February 25, 1959, Serial No. 54,739

Term of patent 14 years

(Cl. D14—3)

Fig. 1

Fig. 3

Fig. 2

Fig. 4

Figure 1 is a front perspective view of a transportable shelter embodying my novel design.

Figs. 2 and 3 are side and rear elevations, respectively, of the transportable shelter shown in Figure 1.

Fig. 4 is a side elevation on a reduced scale, the broken-line showing of a pick-up truck being for purposes of illustration only.

I claim:

The ornamental design for a transportable shelter, as shown and described.
